Frederick C. Fischer.

Inventor

UNITED STATES PATENT OFFICE.

JOHN W. FERGUSON, OF BLOOMFIELD, NEW JERSEY.

SAD-IRON.

1,168,616.

Specification of Letters Patent. Patented Jan. 18, 1916.

Application filed May 28, 1915. Serial No. 30,894.

To all whom it may concern:

Be it known that I, JOHN W. FERGUSON, a citizen of the United States, residing at Bloomfield, in the county of Essex and State 5 of New Jersey, have invented certain new and useful Improvements in Sad-Irons, of which the following is a full, clear, and exact description, such as will enable others skilled in the art to which it pertains to 10 make, construct, and use the same, reference being had to the accompanying drawings, and to numerals of reference marked thereon, forming a part of this specification.

My invention relates to hollow, self-heating sad-irons, in which charcoal, carbon, etc., is used for fuel.

Its main objects are to properly control the draft, and provide suitable means for preventing the ashes which accumulate in 20 the iron, from falling upon and soiling the work.

A further object of my invention is to provide a stand or holder for the iron, which is designed, and by means of which, the 25 proper burning of the fuel is assured.

The invention is fully described in the following specification, in which the accompanying drawings form a part, and in which separate parts of my invention are 30 designated by suitable reference characters in each of the views, in which—

Figure 1 represents a side elevation of my improved iron and stand or rest, the iron being placed on said stand in an inclined 35 position, in order that the air will readily pass through the openings in the rear wall of the iron and out through the flue in the front of the iron, by reason of the flue near the front of the iron being so much higher 40 than the openings in the rear wall of the iron, and also to permit the ashes which may accumulate to have a natural tendency to pass over the base of the body of the iron into the ash receptacle, where they will be 45 caught and prevented from falling out by the removable cover. Fig. 2 represents a rear elevation of the iron. Fig. 3 represents a vertical longitudinal section of the same, taken on lines $x-x$ of Fig. 2, and looking 50 in the direction indicated by the arrow: and Fig. 4 represents a perspective view of the inclined stand or rest without the iron.

Referring to the drawings by reference numerals. 1 represents the body of the sad iron, which, as usual, is hollow, to receive the fuel by which it is heated. For the purpose

of holding the fuel away from the sides of the iron, so as not to choke or obstruct the draft, and to prevent the escape of ashes, soot, etc., from the iron, I provide a removable device 2 having an approximately arcuate flange 3, said flange curving inwardly and downwardly, to provide a flue 4, which extends clear across the rear wall of the body and along the side walls thereof, and terminates at a point adjacent the forward end of the body. The flange 3 terminates a short distance from the inner face of the body 1, to provide a passage 5 through which may emerge the draft from the flue 4 from three sides of the fuel, whereby to provide for a ready combustion of the charcoal within the iron.

The base of the body 1 extends beyond the rear wall of the body, and is provided with an integral flange 6, the same extending upwardly from the base of the body, along the sides and curving upwardly in the rear to provide an ash receptacle 7 located adjacent the opening 8, whereby any ashes which may come out through the opening 8 will be caught by said receptacle and will be prevented from falling upon the article being ironed, by means of a removable cover 9, the sides of which rest upon the side flanges of the ash receptacle, and the end of which is provided with an integral outwardly-extending finger piece 10, designed to be received into a recess 11 located in the upwardly curved flange 6, to properly position said removable cover 9, and to provide means for readily removing the same.

A sliding damper 12, provided with an integral outwardly-extending finger piece 13, and further provided with elongated slots 14, to receive screws 27 secured in the rear wall of the iron, is slidably connected to the rear wall of the iron. The sliding damper 12 has formed therein openings 28 corresponding to the openings or air-inlets 24 in the rear wall of the iron, by which the size of the openings may be regulated by moving said sliding damper 12 along the rear wall of the body of the iron. An integral, outwardly-extending ledge 15 is formed on the lower edge of the sliding member 12, which forms a shoulder to receive the inner edge of the removable cover 9 of the ash pit 7, to prevent accidental displacement of the same.

The cover 16, on its under side, near the rear edge thereof, is provided with an in-

tegral engaging element 29, designed to engage with a projection 17 secured to the rear wall of the iron, which in this instance, is illustrated as a screw, and by means of which the rear edge of the cover is properly positioned and held on the body 1. The front end of the cover 16 is provided with an upwardly-curved extension 18, designed to engage with the nose or front edge 19 of the iron, which extends above the body of the iron, and to which the cover is removably secured in any convenient or desired manner, the space between the under side of the curved portion 18 of the cover 16 and the top of the body of the iron, adjacent to the upwardly-extending nose, forming a flue 20. The handle 21, which may be of any convenient form, is attached to the cover in the usual or any suitable manner.

In the outwardly-extending finger-piece 13 a recess is located, and a spiral spring 30 is located in said recess, which spring bears against the rear wall of the iron, to at all times keep the damper in its adjusted position.

The inclined stand or rest 22 for the iron, has an open-work bottom, through which the bottom of the sad-iron is exposed, and its temperature thereby kept down. It is provided with a pair of long legs 23 at the front, so that when the iron is not in use, and resting on the stand in the inclined position, as shown, any ashes which may accumulate, will have a natural tendency to pass over the base of the body of the iron, into the ash receptacle, where they will be caught and prevented from falling out by the removable cover 9. Suitable integral lugs 25, arranged in close proximity near the rear edge of the stand, and similar lugs 26, arranged near the front edge of the stand, provide means for holding and positioning the iron on the stand. With the iron in this

position on the stand, and the openings in the rear wall of the iron registering with the sliding damper 12, the air will readily pass through the iron and out through the flue in the front, by reason of the opening near the nose being so much higher than the rear openings.

Experience has demonstrated that the combination above described is a practical and efficient one to accomplish the ends sought by this invention. The construction, however, may be varied in detail by those skilled in such matters without departing from the invention.

I claim:

A hollow sad iron, comprising a main body portion, a removable cover therefor, with a flue formed at their front ends, openings or air inlets in the rear wall of said iron forming draft openings, an ash pit integrally formed with the body of the iron and located at the rear thereof, provided with a recess formed in its upwardly curved flange, a removable cover for said ash pit, a sliding damper for regulating the size of the draft openings in the rear wall of said iron, said sliding damper located entirely above the removable cover and provided with a ledge on its lower end adapted to be engaged by the inner edge of the said removable cover and a finger piece integrally formed with said removable cover adapted to rest in the recess formed in the upwardly curved flange of the ash pit for holding said removable cover in position and forming means for removing said cover from said ash pit.

This specification signed and witnessed this 18th day of May, 1915.

JOHN W. FERGUSON.
